UNITED STATES PATENT OFFICE.

CHARLES H. GAGE, OF RICHMOND, WISCONSIN.

CULTIVATOR.

SPECIFICATION forming part of Letters Patent No. 398,959, dated March 5, 1889.

Application filed January 1, 1888. Serial No. 284,351. (No model.)

To all whom it may concern:

Be it known that I, CHARLES H. GAGE, of the town of Richmond, in Walworth county, and State of Wisconsin, have invented a new and useful Improvement in Cultivators, of which the following is a specification.

This invention relates to that class of cultivators known as "sulky" or "riding" cultivators designed to cultivate both sides of a row of corn at the same time.

The object of my invention is to produce a cultivator so constructed as to have an easy lateral as well as vertical movement of the teeth, which can be readily guided while in use by the feet of the operator sitting on the seat, thereby controlling the teeth and conforming the furrow made by each to the slope of the row being cultivated without changing their adjustment to the machine, and at the same time to have each tooth maintain its relative angle with the line of draft, as well as other improvements, hereinafter described, all of which constitute the subject-matter of my invention.

In the accompanying drawings, Figure 1 represents a side elevation of a wheel-cultivator embodying my invention, the forward part of the tongue being broken away. Fig. 2 represents a plan view of the drag-bars and the parts attached. Fig. 3 represents a detail front elevation of the arched hanger and the device for attaching the drag-bars thereto. Fig. 4 represents a plan view of the axle, the tongue, and said hanger. Fig. 5 represents a front elevation of the axle, its journals, and the brace F for the drag-bars, the lower part of said brace being broken away. Figs. 6, 7, 8, 9, 10, and 11 represent detail views of the devices for attaching a shovel or cultivator-tooth to one of the drag-bars, Fig. 10 showing the tooth or shovel also, and Fig. 11 only the tapering plug.

Similar letters refer to similar parts throughout the drawings.

A represents the wheel of the cultivator; B, the axle, with its arms b b, upon which the wheel A revolves.

C C represents the tongue, made of two pieces of wood coming together at the front ends, the rear being spread apart and bolted to the axle B.

D D represent the two pieces of timber upon which the seat W is secured, the front ends of these seat-pieces being bolted to the prongs of the tongue in front of the axle, extending back across the top of the axle a distance sufficient to allow the seat to be in the proper position over the drag-bars.

E represents the lever, which operates with the ratchet K, and being pivoted to it by the bolt d and connected at its forward end to the drag-bars by the rod L, which hooks into the eyebolt m in the front end of the lever, and also hooks into the hole a in the cross-plate g. This lever is used for raising and lowering the drag-bars, the handle of said lever being in the rear of the axle and in convenient reach of the operator.

F represents a brace, as shown in Fig. 4, which slides through, and is held in place by the loops v v on the rear side of the axle B, as shown in Fig. 7, the lower ends of which drop down and pass through the holes h h in the cross-plate on top of the drag-bars. The office of this brace F is to regulate the drag-bars on each side of the row being cultivated.

G represents a rod or brace bent in the form of a crank at each end, as shown in Fig. 3. Its shaft part lies across the top of the tongue, as shown in Fig. 5, and is fastened to the said tongue on each side by the hasps q q. The crank ends of this brace drop down and pass through the hole j in the device H, as shown in said figure. The ends project through far enough that they may take on them the front end of the brace I, as shown in Fig. 1, the brace being held at its front end by a nut which is screwed onto the end of the brace G, and at its rear end by a bolt passing through it and the axle, as shown in Fig. 1. The office performed by this brace G is not only to securely hold the device H in position, but also to form a pivot or joint, on which the drag-bars, when attached to said device H, can turn either up or down, and thus conform to the uneven surface of the land being cultivated.

H represents the device for holding the front ends of the drag-bars, as shown in Fig. 2. It is made of iron, and at each end there is a hole to receive the bolt i, which secures the front end of the drag-bar to the device. On the top of this device there is a brace, O,

which extends from the top of said device back to the drag-bar. The front end of this brace is held in position by the bolt *i*, which holds the front end of the drag-bar to the device *H*, as shown in Fig. 2, thus forming a pivot upon which the said drag-bars are permitted to turn in a lateral movement and in either direction. It is this pivot which provides for the lateral movement of the drag-bars, in order that the cultivator, when in operation, may conform readily and easily to the zigzag direction of the rows without changing the course of the team. On the front side of this device *H* is a protrusion extending from the center of the front side thereof far enough to enable the large hole *j* to run through it parallel with the device. It is this hole *j* and the lower end of the crank-shaped brace *G* when it is put through it that form the pivot upon which the drag-bars have their upward and downward movement, and which permit the drag-bars to conform to the uneven surface of the land being cultivated, and permit the wheels to drop into the low places and to rise on the high places without affecting the running depth of the shovels.

M represents the front end of the drag-bar, and *N* the rear end. These are wood, and are nearly of the same length, being lapped together about eight inches and secured by the bolt *T*, the front end of the rear piece, *N*, being under the rear end of the front piece, *M*, and having a brace, *P*, from its lower side extending up and bolted to *M*, and a brace, *r*, from the upper side of *M* down to the upper side of the piece *N*, and securely bolted in position by the pivoted bolt *T*, as shown in Fig. 1. The front end of *M* is bolted to the device *H* by the bolt *i* and braced by the brace *O*, as described. Attached to the rear end of the piece *N* are two shovels, being fastened thereto, as hereinafter described, the rear shovel being attached to the outside and the front shovel being attached to the inside of the piece *N*, as shown in Fig. 1. The drag-bar thus formed, it will be seen, has two pivoted points—one in the center and one at the front end. These pivoted points provide for the lateral movement either way of the drag-bars, and also of the shovels attached thereto, without changing the line of draft, and, if desired by the operator, the furrows made at the same time conform to the shape of the row being cultivated.

There are four drag-bars—two on each side of the cultivator—all made of similar material and in the same manner, and are attached to the other parts of the cultivator in the same way, and on each of the drag-bars are two shovels. Back of the pivoted center of each drag-bar is a plate of iron, *g*, extending from one drag-bar to the other and bolted to the top of each in such a way as to hold the drag-bars parallel with each other, and on the front edge of this plate *g* is a hole, *a*, for receiving the lower end of the rod, attached

to the end of the hoisting-lever *E*, to which it is secured, and by which the drag-bars are raised and lowered, while in the center of this plate *g* are holes *h*, into which the end of the rectangular brace *F*, Fig. 4, is inserted. This brace keeps the two sets of drag-bars a uniform distance apart when in use, the upper side of the brace sliding through the staples *v v*, fastened to the rear side of the axle *B*. Still farther back, and between the shovels and on the top of the drag-bars, is another iron plate, *x*, extending from one drag-bar to the other, which is securely bolted to each drag-bar, and to this iron plate *x* is securely bolted the foot-rest *S*, as shown in Fig. 2. The driver, while seated in the seat, by placing his foot on the foot-rest *S*, can gage the furrows made by the shovels so as to have them near to or remote from the row being cultivated, while at the same time the main furrows will be parallel with the line of draft of the machine.

Figs. 6, 7, 8, and 9 show different sides of the same piece of cast-iron. In these drawings, *A'* represents a piece of cast or malleable iron with flanges *e e* on each side and a large round hole, *x'*, through its center, the piece *A'* being from one to one and a half inch in thickness. This hole *x'* is tapering, being larger on the outside, as shown in Fig. 9, and smaller on the inside, as shown in Fig. 7. Into this hole *x'* is inserted the corresponding tapering pin, *B'*, which is also made of metal, provided with a recess, *d'*, at its largest end for the shaft of the shovel *D'* to set into, and a round hole, *c'*, through its center, so that when *A'* is placed against the side of the drag-bar the flanges *e' e'* projecting over each side, and *B'* is inserted into the hole *x'* in *A'*, and the shovel-shaft *D'*, with a hole through its top end, is laid into the recess *d'*, and a bolt is put through the hole in *D'* and through the hole *c'* in *B'* and through the drag-bar *N*, and the nut is screwed down sufficiently tight, a device is formed for holding in position to the side of the drag-bar the shovel of said cultivator, so that when the tooth or shovel meets an obstruction of sufficient resistance the shovel of said cultivator will turn back, and the shovel will pass over said obstruction without breaking or injuring any part of said cultivator. After said obstruction is passed, the device and shovel can be readily and easily adjusted and the machine proceed as before.

Having described my invention, what I claim as new, and desire to secure by Letters Patent, is as follows:

1. A set of cultivator drag-bars, each made in two sections jointed end to end for lateral vibration, in combination with couplings which connect the parallel sections in pairs, braces extending from each forward section to the rear section of the same drag-bar, a cultivator-frame, and a hanger which suspends said drag-bars from said frame, but allows vertical vibration, substantially as set forth.

2. The combination, with the main frame of the cultivator, of the arched bail or hanger G, the braces I, the coupling H, the jointed or sectional drag-bars, the perforated cross-plate 5 g, and the arched brace f, sliding in guides upon the axle, substantially as set forth.
3. The combination, with the main frame and the arched hanger G, of the jointed drag-bar frames, the couplings H, the sliding brace 10 or arch F in rear of the joint, the plate g, to adjustably connect the drag-bars and the lifting-lever, and the cross-bar x with foot-rests S, substantially as shown and described.
4. The cultivator-frame and the arched 15 hanger, in combination with the jointed frames or drag-bars M N, the couplings H, the cross-bars g and x upon the rear section of the drag-bars, the sliding arched brace f, adjustable in plates g, and the lifting-lever, sub- 20 stantially as shown and described.
5. The combination, with the frame and the arched hangers G, having horizontal spindles, of the cross-barrel couplings H, the jointed drag-bars, the rear section, N, having the cross-bars g x, the adjustable connecting-bar F, and 25 the foot-rests S, whereby said rear section may be swayed laterally, turning upon the pivot-bolts T of the jointed frame, as shown and described.
6. The frictional standard-holder consisting 30 of flanged plate A', having the tapered opening a, the tapering pin B', having the recess d' and a central perforation, and a bolt and nut, whereby all the parts are secured to the drag-bar and the shovel-standard held by 35 friction so as to yield to obstructions.

CHARLES H. GAGE.
